COOKING RANGE WITH VENTILATING HOOD

Filed April 10, 1945

UNITED STATES PATENT OFFICE

2,482,952

COOKING RANGE WITH VENTILATING HOOD

Harry L. Warren, South Pasadena, Calif., assignor
to Southern California Gas Company, Los Angeles, Calif., a corporation of California

Application April 10, 1945, Serial No. 587,527

11 Claims. (Cl. 126—299)

1

My invention relates to cooking range with ventilating hood, and among the objects of my invention are:

First, to provide a cooking range with ventilating hood which is designed to vent not only an oven or broiler, or both, but to vent the fumes from the top of the range as well.

Second, to provide a cooking range with ventilating hood and manifold system which is particularly designed for use in conjunction with an exhaust fan, but which is not dependent upon functioning of the exhaust fan in order to use the range, whether the top thereof, or the oven or broiler.

Third, to provide a cooking range with ventilating hood which incorporates a warming shelf for heating dishes, or for maintaining the food warm between cooking and serving.

Fourth, to provide a cooking range with ventilating hood, wherein the heat from the oven or broiler may be introduced into the room containing the range, rather than be exhausted outside, so that the range may be employed as a space heater.

Fifth, to provide a cooking range with ventilating hood and associated manifold system which does not require dampers or other valve control means to effect the desired flow of flue gases and vapors.

Sixth, to provide a cooking range with ventilating hood and associated manifold system which is inherently safe, in that should there be a back flow therethrough, such flow is not directed into the oven or broiler but is relieved, and further, under normal conditions of operations, draws ambient air from the room into the ventilator system as well as the flue gases and vapors, to reduce the average temperature within the ventilator system.

With the above and other objects in view, reference is directed to the accompanying drawings, in which:

Fig. 1 is a fragmentary perspective view of the back side of a range equipped with my ventilating hood with a portion of the hood shown in section.

Fig. 2 is a fragmentary sectional view taken substantially through 2—2 of Fig. 1.

Fig. 3 is a sectional view in plan taken substantially along the line 3—3 of Fig. 1.

My cooking range with ventilating hood may be adapted to various styles and types of kitchen ranges. In the illustration, a range structure 1 is shown, which includes a top plate or work surface 2 having a series of burners 3, in this case, four burners arranged in a single row. Below

2

the top plate 2 is located an oven 4 and a broiler 4a indicated by dotted lines in Fig. 3.

A back plate 5 extends upwardly from the top plate 2, and its upper end is provided with a forwardly directed and slightly upwardly inclined baffle plate 6. Over the baffle plate 6 is positioned a hood or cover 7 which is preferably flat to form a shelf. The forward edge of the hood is provided with a depending skirt or flange 8 overhanging the forward extremity of the baffle plate 6 and spaced therefrom to form an entrance slot 9. The baffle plate and hood form a diverging passageway occupying the width of the range and extending to the rear thereof, and terminating in an outlet slot 10.

The outlet slot 10 is covered by a manifold 11 secured to the rear side of the range and extending approximately the width thereof. The manifold 11 includes a central chamber 12 having downwardly converging lower walls 13, and communicates with an exhaust duct 14 which extends down the back side of the range structure. The exhaust duct communicates with the intake side of a suitable exhauster 15 operated by an electric motor 16. The exhauster 15 discharges into an exhaust pipe 17 which may lead under the floor of the kitchen and extend laterally to a suitable discharge point.

The manifold 11 is provided with compartments 18 at each end, and baffle lips 19 continuing from the lower walls 13 project into these compartments. Ducts 20 extend downwardly from the end compartments 18 and terminate in intake canopies or boxes 21 secured to the rear side of the range structure. The forward sides of the intake canopies 21 are formed by the range structure itself, and the lower sides of the intake canopies are completely open as indicated by 22, to form relief openings of large area. Slots 23 are provided in the range structure and communicate between the oven 4 or broiler and the corresponding intake canopies.

Operation of the cooking range with ventilating hood is as follows:

During operation of the range and oven without operation of the exhauster, the gases formed in the oven pass through the slots 23 up through the ducts 20 and into the manifold 11 without substantial restriction and without drawing a material quantity of air up through the relief opening 22. When the fan is in operation, the same flow occurs and the influence of the exhauster is to draw air through the entrance slot 9 of the hood as the parts are proportioned so as to give less frictional resistance to flow of air

under this condition of operation through the entrance slot 9 and hood structure than is offered to the flow of air through the duct 20 and over the baffle 19. This tends to reduce the temperature. During operation of the exhauster, air, vapor and fumes from the top of the stove are drawn through the entrance slot 9, and discharge from the outlet slot 10 into the manifold 11 and continue down the exhaust duct 14—this flow likewise being indicated by solid arrows in Fig. 1.

When the exhauster is not in operation and the oven or broiler, or both are functioning, the gases and vapors issue from the slots 23, flow upwardly through the ducts 20 around the baffle lips 19 and continue upwardly through the manifold 11 into the slot 10 and discharge from the slot 9 at the forward side of the hood cover, as indicated by dotted arrows in Fig. 1.

Should there exist for any reason, a higher pressure in the manifold 11 than exists at the intake canopies 21, the gases from the oven or broiler are free to flow downwardly and out the relief openings 22. Thus irrespective of the pressure conditions in the ventilating hood structure, the oven and broiler as well as the top of the stove, may continue to be used without danger.

It will be noted that the oven or broiler is not prevented from use as a space heater, by reason of the ventilating canopy, for as pointed out above, when the exhauster 15 is not in operation, the gases from the oven or broiler discharge from the slot 19 and into the room containing the stove.

In the course of cooking a meal either on top of the stove, or by means of the broiler or oven, it is often desirable to heat plates, or maintain the food heated between cooking and serving. The shelf afforded by the hood cover 7 admirably serves this purpose, as the rising heat from the top of the stove may be employed to heat the hood cover 7 when the exhauster is in operation, or the heat from the oven or broiler may be so employed when the exhauster is not in operation.

Many other embodiments of the invention may be resorted to without departing from the spirit of the invention.

I claim:

1. A hood structure for ranges having an exposed cooking surface and an enclosed cooking compartment below, said hood structure comprising: a hollow shelf extending over said cooking surface from the back side thereof and having an opening thereto along its extreme forward margin; a manifold communicating with the interior of said shelf along its back edge and depending therefrom; a duct extending upwardly from the enclosed cooking compartment to said manifold; and an exhauster having its intake side connected with said manifold to withdraw gases simultaneously from said exposed cooking surface through said hollow shelf and manifold and to withdraw gases from said cooking compartment through said duct and said manifold.

2. A hood construction as set forth in claim 1, wherein said duct has a relief opening below its communication with said enclosed cooking compartment whereby reversed flow of air through said ducts is caused to bypass said enclosed cooking compartment and whereby cooling air is entrained with gases discharging upwardly in said duct from said cooking compartment.

3. A hood construction as set forth in claim 1, wherein said duct, manifold and hollow shelf define a free passageway communicating with the forward opening of said hollow shelf whereby, during non-operation of said exhauster, gases

from said enclosed cooking compartment may flow through said manifold, through said shelf and out said opening.

4. A hood structure for ranges having an exposed cooking surface and an enclosed cooking compartment therebelow, said hood structure comprising: a rear wall extending upwardly from said cooking surface; a hollow shelf extending forwardly from said rear wall and having a depending forward skirt and an opening immediately behind and shielded by said skirt; a depending manifold at the back side of said wall having its upward extremity communicating with the rear side of said shelf along its length; a duct extending from the cooking compartment to the underside of said manifold; and an exhauster having its intake side connected with said manifold to withdraw gases from said exposed cooking surface through said hollow shelf and to withdraw gases from said cooking compartment through said duct.

5. A hood construction as set forth in claim 4, wherein said duct is provided with a relief opening below its communication with said enclosed cooking compartment whereby reversed flow of air through said ducts is caused to bypass said enclosed cooking compartment and whereby cooling air is entrained with gases discharging upwardly in said duct from said cooking compartment.

6. A hood construction as set forth in claim 4, wherein said duct, manifold and hollow shelf define a free passageway communicating with the forward opening of said hollow shelf whereby, during non-operation of said exhauster, gases from said enclosed cooking compartment may flow through said manifold, through said shelf and out said opening.

7. A hood structure for ranges having an exposed cooking surface with a row of burners therealong and enclosed oven and broiler compartments therebelow, said hood structure comprising: a rear wall extending upwardly from said cooking surface; a hollow shelf extending forwardly from said rear wall and having a depending forward skirt overhanging said burners, said skirt and underside of said shelf defining a slot communicating with the interior of said shelf and extending the length of said cooking surface; a manifold at the back side of said wall communicating with the rear side of said shelf along its length, to receive gases from or discharge gases through said slot, said manifold including downwardly converging lower walls and baffled passages at its lateral extremities; ducts communicating between said oven and broiler compartments and said baffled passages; an exhaust duct leading from the central portion of said manifold; and an exhaust fan communicating with said exhaust duct to withdraw gases from said compartments and from said cooking surface through said shelf.

8. A hood structure for ranges having an exposed cooking surface with a row of burners therealong and enclosed oven and broiler compartments below, said hood structure comprising: a rear wall extending upwardly from said cooking surface; a hollow shelf extending forwardly from said rear wall and having a depending forward skirt overhanging said burners, said skirt and underside of said shelf defining a slot communicating with the interior of said shelf and extending the length of said cooking surface; a manifold at the back side of said wall communicating with the rear side of said shelf along its

length; a duct extending from the cooking compartment to the underside of said manifold; and an exhauster having its intake side connected with said manifold to withdraw gases from said exposed cooking surface through said hollow shelf and to withdraw gases from said cooking compartment through said duct.

9. A hood structure for ranges having a series of exposed cooking burners and an enclosed cooking compartment therebelow, said hood structure comprising: a wall behind said exposed cooking burners; a hollow shelf extending forwardly from said back wall over said burners and defining openings along its forward and rearward margins, said openings being in communication through said shelf, the upper wall of said shelf forming a utensil supporting surface; a manifold communicating with said shelf and disposed rearwardly of said wall; a duct communicating between said manifold and said enclosed cooking compartment; means forming an exhaust passage communicating with said manifold; and an exhauster in said passage for withdrawing vapors and fumes simultaneously from said exposed burners and said enclosed compartment.

10. A hood structure for ranges having a series of exposed cooking burners and an enclosed cooking compartment therebelow, said hood structure comprising: a wall behind said exposed cooking burners; a hollow shelf extending forwardly from said back wall over said burners and defining openings along its forward and rearward margins, said openings being in communication through said shelf, the upper wall of said shelf forming a utensil supporting surface; a manifold communicating with said shelf and disposed rearwardly of said wall; a duct communicating between said manifold and said enclosed cooking compartment; means forming an exhaust passage communicating with said manifold; and an exhauster in said passage for withdrawing vapors and fumes simultaneously from said exposed burners and said enclosed compartment; said duct being in communication with said hollow shelf through said manifold whereby, when said exhauster is inactive, the heated products issuing from said enclosed cooking compartment dis-

charge from the forward opening of said shelf and heat the utensil supporting wall thereof.

11. A hood structure for ranges having a series of exposed cooking burners and an enclosed cooking compartment therebelow, said hood structure comprising: a wall behind said exposed cooking burners; a manifold disposed behind said wall; a hollow shelf communicating with said manifold and extending forwardly from said wall over said burners, said shelf terminating in an opening adapted to admit fumes from said burners and volatile substances which may be driven off during cooking of materials on said burners; a duct leading upwardly from said enclosed cooking compartment to said manifold; and means for exhausting said manifold to draw simultaneously fumes from said enclosed cooking compartment and from said exposed cooking burners, said exhausting means capable of being rendered inactive, whereby heated products from said enclosed cooking compartment flow upwardly through said duct, manifold, and out the forward opening of said shelf.
